UNITED STATES PATENT OFFICE.

JOHN SCHUMACHER, OF LOS ANGELES, CALIFORNIA.

PROCESS AND MEANS FOR MAKING PLASTER-BOARD AND THE LIKE.

1,379,940.

Specification of Letters Patent. Patented May 31, 1921.

Application filed May 10, 1920. Serial No. 380,097.

To all whom it may concern:

Be it known that I, JOHN SCHUMACHER, a citizen of the United States, residing at Los Angeles, in the county of Los Angeles and 5 State of California, have invented new and useful Improvements in Processes and Means for Making Plaster-Board and the like, of which the following is a specification.

This invention relates to an improved 10 process and means of making and handling plaster board. Such board comprises a sheet of paper or paper board and a coating of plastic material applied thereto. As is well known in this art, the plastic material may 15 include as its ingredients, plaster, cement, or compositions of the same applied to the sheet in its plastic form and then allowed to set, the plastic material adhering to the sheet in its final shape as a stiff plaster 20 board.

In the manufacture of such plaster board, it is the common practic to continuously feed sheets of paper between which the plastic material is interposed. In such apparatus 25 the paper and plastic material, are commonly fed from a stationary structure upon a conveyer, severed into initial lengths and piled on trays for convenience in handling during the final steps. Such arrangement 30 of apparatus requires a large floor space and much handling of the plaster board, which, in its soft state, requires skill and care. Trays or receptacles for the plaster board must be moved from place to place in 35 loading and following out the various steps of the process.

It is the primary object of this invention to provide a process and means to carry out such process, whereby apparatus for initially 40 forming the plaster board may be moved with respect to the receivers for the board, the soft board flowing upon the receivers while the latter are stationary.

The above mentioned objects together 45 with other objects and corresponding accomplishments may be obtained by means of the assemblage, arrangement and aggroupment of means and mechanisms illustrated in the accompanying drawings, in which:

50 Figure 1 is a side elevation of apparatus for conveniently carrying out the steps of the process; Fig. 2 is a cross-section as seen on the line 2—2 of Fig. 1; Fig. 3 is an enlarged fragmentary section as seen on the line 3—3 of Fig. 2; Fig. 4 is a plan view of the structure shown in Fig. 3; Fig. 5 is a

diagrammatic section as seen on the line 5—5 of Fig. 4; Fig. 6 is a section taken on the line 6—6 of Fig. 3; Fig. 7 is a section taken on the line 7—7 of Fig. 3; Fig. 8 is an 60 enlarged section of the reversing gearing taken on the line 8—8 of Fig. 7; and Fig. 9 is a section taken on the line 9—9 of Fig. 1 showing the means for severing the board 65 between the receiving cars.

Referring more particularly to Figs. 1, 2, and 9, A indicates a hopper in fixed position for supplying plastic material to tubs indicated generally by B. These tubs are supported upon a framework C. A traveling 70 hoist D is provided for the purpose of moving the tubs B to and from plaster board forming mechanism E. The mechanism E is mounted to travel transversely of the structure upon a traveling platform F. The 75 platform is mounted for traveling longitudinally of the structure upon a girder framework G. Thus, the plaster board forming mechanism is mounted to travel transversely and longitudinally overhead. 80 Disposed beneath the path of travel of the plaster board forming mechanism are cars carrying receiving trays, all being indicated generally by H. Also mounted for travel upon the girder framework is a platform J, 85 upon which is mounted for travel a severing means K, whereby the board may be severed between trays.

Mounted above the hopper structure A is a composition mixing trough 12 having mixing blades 13 rotatably mounted therein and driven by suitable means. A water supply pipe 14 is provided above the mixing trough, and adjacent to the latter is a platform 15 for a mixing operator. The platform is also 90 convenient for holding the ingredients indicated by 16, facilitating the charging of the mixer and the handling of the ingredients used in the plastic composition. The hopper A is provided with a spout 17 equipped with 95 a suitable discharge gate 18.

Mounted upon a platform 19 below platform 15 is a framework carrying rails 20. The tubs B each comprise a receptacle 21 girded by a frame 22, upon which are journaled wheels 23. The tubs are supported upon the rails 20 through the wheels 23 which ride thereon. Thus, a tub in empty condition may be placed upon one of the ends of the rails 20, then moved beneath the 105 hopper spout 17, filled with the plastic composition and then moved to the other ends 110

of the rails in position to be transferred to the plaster board forming mechanism. As shown herein, there is room for three tubs on the rails, one may be empty, the other in position to be filled, and the other in filled position ready to be transferred to the plaster board forming mechanism.

Extending transversely of the structure and disposed above the rails 20 is a rail 24. 10 Mounted upon the rail for travel is the hoist D having an arm 25 adapted to be engaged with hooks 26 on the tubs. Thus, the tubs may be lifted from the rails 20 and transferred to the plaster board forming mechanism 15 or vice versa.

Referring to the girder structure G, it comprises columns 29 suitably braced and supporting girders 30. The girders are arranged in two parallel rows, each row having a rail 20 31 mounted thereon. The rails provide ways for the travel longitudinally of the cutting mechanism and the platform F.

The platform F comprises a rectangular frame 32 spanning the girders 30. Journaled upon the frame at the corners thereof are wheels 33 mounted upon rails 31, so that the platform can travel back and forth upon the girder structure. The forward wheels constitute driving wheels, and fixed to the 25 axles thereof are sprocket wheels 34. The wheels 34 are geared to wheels 35 by means of chains 36. Each wheel 35 is fixed to the end of a shaft 37, best shown in Figs. 6 and 7. Shaft 37 is driven through a gearing 30 35 later described. Mounted upon the frame 32 are parallel rails 38 forming ways for the travel of the plaster forming mechanism.

The plaster forming mechanism comprises a base frame 39 supported upon 40 wheels 40 journaled thereon. The wheels 40 ride upon the rails 38, so that the plaster forming mechanism can travel along the platform F transversely of the structure. 45 Each of a pair of wheels 40 upon opposite sides of the frame 39 are fixed to stub axles 41, best shown in Figs. 3, 4, and 7. Fixed to each axle 41 is a spur gear 42. Each spur gear is in mesh with a pinion 43. The pinion gears 43 are fixed to a shaft 44. Fixed 50 to the shaft 44 is a sheave wheel 45 serving to drive the shaft and operated by means of a chain 46 passing thereover. As the plaster forming mechanism is moved transversely of the structure at intervals to feed plaster board to trains of cars arranged parallel, it is sufficient to move the plaster board forming mechanism by hand power.

Secured to corresponding beams on the 60 frame 39 are triangular plates 48, see Figs. 1, 3, and 7. At the bottom of the plates are bushings 49 and 50. Shaft 37 is journaled in bushing 50. Rotatably mounted in bushing 49 is a sleeve 51, to which is secured a sprocket wheel 52. The inner end

of sleeve 51 is provided with clutch jaws. Fixed to sleeve 51 is a bevel gear 53. Spaced therefrom and rotatably mounted upon the shaft 37 is a similar bevel gear 54 having a clutch jaw. Meshing with bevel gears 53 70 and 54 is a bevel gear 55 rotatably secured to a plate 56 extending between plates 48. It is obvious that gear 55 will drive gears 53 and 54 in opposite directions. Splined to shaft 37 and disposed between gears 53 and 54 is a clutch sleeve 57. Sleeve 57 is provided upon opposite ends with jaws for engagement with either gear 53 or gear 54. Thus, if the sleeve is engaged with gear 54 shaft 37 will be driven in one direction, and 80 if the sleeve is engaged with gear 53, the shaft will be driven in the opposite direction. Motion is transmitted from the shaft 37 to the drive wheels 33 of the platform, and the latter is caused to move backward 85 or forward. A shift lever 58 is secured to the sleeve 57. The shift lever is connected by a link 59 to a control lever 60, whereby an operator by shifting the clutch may cause the platform to travel forward or 90 backward at will or stop. Sprocket wheel 52 is geared to a wheel mounted upon a drive shaft by means of a chain 61. Mounted upon the beams of the frame 39 are pillow blocks 62, in which is journaled a shaft 95 63. The shaft 63 overhangs one of the pillow blocks and is journaled in a bearing block 64. Fixed to shaft 63 and inside of block 64 is a worm wheel 65. Meshing with worm wheel 65 is a worm mounted upon a 100 shaft 66 driven by a motor 67. Also fixed to shaft 63 is a double sprocket wheel 68, over which passes chain 61, driving gear 52 on shaft 37.

A roller 70 is fixed to shaft 63 so as to be 105 driven thereby. Coöperating with roller 70 is a pressure roller 71, see Fig. 5, journaled in sliding blocks 72 mounted in ways upon pillow blocks 62. Blocks 72 are resiliently held in position by means of 110 springs on either side thereof, and their position is adjusted by means of hand wheels 73. This provides for controlling the thickness of the plaster board. Rotatably mounted upon the framework 39 are rolls of paper 115 74 and 75. A web of paper is led from roll 74 around a guide roller 76 and over roller 70. A web of paper from roller 75 is led over a guide roller 77 and over pressure roller 71. Embracing a portion of 120 roller 70 is a box 78, the bottom thereof being open and one side being cut away to permit a portion of pressure roller 71 to pass therein. Box 78 serves to receive the plastic composition from a tub 21 and to 125 guide it to and between the webs of papers passing from rolls 74 and 75. The bottom of each tub is provided with a spout 79 and a gate valve 80 to control the flow of plastic composition from the tub to the box. 130

From the construction just described, it is obvious that the plastic composition is fed into box 78 and therefrom between the sheets of paper. The web from roll 74 is positively driven by its friction with the surface of roller 70. The paper adhering to the other surface of the plastic composition will be assisted in its travel from roll 75. The initially formed soft plaster board 5 is delivered to a conveyer which is supported from the frame 39 and extends downwardly toward the cars to which the plaster board is delivered.

The conveyer comprises a frame work 81 pivotally supported upon the frame work 39. The upper ends of the side members of the framework 81 are pivotally mounted upon a shaft 82. Shaft 82 is journaled in frame 39 and has fixed thereto a drive roller 83 for the endless conveyer 84. Adjustably mounted at the far end of the frame 81 is a roller 85 over which conveyer 84 passes. Fixed to the end of shaft 82 is a pinion 86 meshing with a gear 87. Gear 87 is fixed 10 to a stub shaft having secured thereto a sprocket wheel 88. Sprocket wheel 88 is geared by a chain 89 to the sprocket wheel 68 mounted on shaft 63. This provides for driving roller 83 at the speed corresponding 15 to roller 70. Secured to the conveyer frame adjacent its far end is a bail 90 having a cable 91 secured thereto and passing over an idler wheel 92 journaled in frame 39. Secured to the free end of cable 91 is a 20 counterweight 93. By means of this construction, the delivery end of the conveyer 25 may be raised and lowered.

Referring to Figs. 3 and 5, it will be noted that plaster board passes from the plaster board forming mechanism upon the conveyer, is carried therealong and delivered from the end. The process is continuous. When a tub 21 mounted on the plaster forming mechanism is emptied, the latter is moved to one end of the platform F adjacent the framework 19. The hoist D is then lowered to engage the empty tub, and the latter is lifted and placed upon the rails 20 at their left hand ends as shown in Fig. 2. 25 A full tub 21 is then engaged by the hoist and lowered to the plaster board forming mechanism. A tub which has been filled and rests upon the rails 20 is then moved to the right hand end thereof, riding upon the rails 20. The plaster board forming mechanism is moved transversely of the structure so that the conveyer is disposed over a train of cars having trays to be filled. The end of the conveyer is disposed a short 30 distance above the surface upon which the board is to be laid. The platform is then moved to one end of the structure by means of the motor mechanism and the plaster forming mechanism started as well as the platform, so that the latter travels to the

other end of the train. In its travel a length of plaster board is laid from one end of the train to the other. When the other end of the train is reached, the plaster board is severed and the platform starts 70 in the reverse direction. When the other end of the train is reached the board is severed, and this is continued until the requisite number of layers of plaster board have been stacked, one on top of the other. 75

It is necessary to sever the plaster board between cars, in order that the receivers or trays thereon may be handled independently. For this purpose a cutting mechanism is provided. Referring particularly to 80 Figs. 1 and 9, this may comprise a platform J mounted on wheels and traveling longitudinally of the structure. The platform is equipped with driving wheels and gearing similar to that for the plaster forming 85 mechanism. However, it is operated manually from a sheave wheel 94 and a chain 95. Traveling upon the platform J is a frame indicated generally by 96. This frame is moved back and forth upon the platform 90 through gearing and a sheave wheel 97 rotated by means of a chain 98. Suspended from the frame 96 is a saw frame 99 having a circular saw 100 rotatably mounted at the lower end. The saw is operated by means 95 of a belt 101 driven from a motor 102 mounted upon frame 96. A link may depend from the frame and be connected to a starting switch for the motor. It is obvious that the platform J and the cutting 100 mechanism K may be moved to a point over a train of cars, the motor 102 started, and the frame 99 moved so that the saw 100 cuts the piles of plaster board, separating those on adjacent cars. 105

It is obvious that this invention provides for a process to make and handle plaster board by moving the plaster board forming mechanism back and forth so as to deliver the plaster board in layers to receivers. 110

What I claim is:

1. The herein disclosed process of handling plaster board and the like, which consists in continuously forming flexible plaster board, reciprocating the forming mechanism 115 above a receiver, and flowing said plaster board upon said receiver during travel of said mechanism so that the board is stacked in layers on said receiver.

2. The herein disclosed process of handling plaster board and the like, which consists in continuously forming plaster board, reciprocating the forming mechanism above a receiver, flowing said plaster board upon 120 said receiver during travel of said mechanism, and severing said plaster board at the ends of its travel in either direction. 125

3. The herein disclosed process of handling plaster board and the like, which consists in continuously forming flexible plaster 130

4
board, horizontally reciprocating the forming mechanism above a receiver, and laying the plaster board downwardly upon said receiver during the travel of said mechanism, 5 so that the board is stacked in layers on said receiver.

4. The herein disclosed process of handling plaster board and the like, which consists in continuously forming plaster board, 10 horizontally reciprocating the forming mechanism above a receiver, laying the plaster board downwardly upon said receiver during the travel of said mechanism, and severing said plaster board at the ends 15 of its travel in either direction.

5. The herein disclosed process of handling plaster board and the like, which consists in forming flexible plaster board, reciprocating the forming mechanism above a 20 receiver, flowing said plaster board upon said receiver during the travel of said mechanism, and moving said mechanism transversely to its reciprocating travel, whereby parallel rows of plaster board may be 25 stacked on said receiver.

6. The herein disclosed process of handling plaster board and the like, which consists in forming flexible plaster board, reciprocating the forming mechanism above a 30 receiver, flowing said plaster board upon said receiver during travel of said mechanism, moving said mechanism transversely to its reciprocating travel, and severing said plaster board at the ends of its travel in 35 either direction, whereby parallel rows of plaster board may be stacked on said receiver.

7. The herein disclosed process of handling plaster board and the like, which consists in forming flexible plaster board, horizontally reciprocating the forming mechanism above a receiver, laying said plaster board downwardly upon said receiver during the travel of said mechanism, and moving 40 said mechanism transversely to its reciprocating travel, whereby parallel rows of plaster board may be stacked.

8. The herein disclosed process of handling plaster board and the like, which consists of forming flexible plaster board, horizontally reciprocating the forming mechanism above a receiver, laying the plaster board downwardly upon said receiver during the travel of said mechanism, severing 50 said plaster board at the ends of its travel in either direction, and moving said mechanism transversely to its reciprocating travel, whereby parallel rows of plaster board may be stacked on said receiver.

60 9. In a plaster board apparatus, a traveling plaster board forming mechanism comprising means to continuously advance and convey plaster board to a surface upon which it is laid.

65 10. In plaster board apparatus, the com-

bination of an elevated structure, a plaster board forming mechanism mounted to travel longitudinally thereof comprising means to continuously advance and convey plaster board, and a receiver disposed beneath said 70 structure on which said plaster board is piled.

11. In a plaster board apparatus, the combination of an elevated structure, a plaster board forming mechanism mounted to travel 75 longitudinally and transversely thereof, and a receiver disposed beneath said structure on which said plaster board is piled.

12. In plaster board apparatus, the combination of an elevated way, a platform 80 mounted thereon to travel longitudinally thereof, plaster board forming mechanism mounted to travel on said platform transversely of said way, and receivers disposed beneath said structure on which said plaster 85 board is piled.

13. In plaster board forming apparatus, the combination of an elevated structure, a plaster board forming mechanism mounted to travel longitudinally thereof, receivers 90 disposed beneath said structure, and a conveyer secured to said plaster board forming mechanism to continuously deliver said plaster board therefrom to said receivers on which said plaster board is placed. 95

14. In a plaster board forming apparatus, the combination of an elevated structure, a plaster board forming mechanism mounted to travel longitudinally and transversely thereof, receivers disposed beneath said 100 structure, a conveyer secured to said plaster board forming mechanism to deliver said plaster board therefrom to said receivers on which said plaster board is placed.

15. In a plaster board apparatus, the combination of an elevated way, a platform mounted thereon to travel longitudinally thereof, plaster board forming mechanism mounted to travel on said platform transversely of said way, receivers disposed beneath said structure, and a conveyer secured to said plaster board forming mechanism to deliver said plaster board therefrom to said receivers. 110

16. In plaster board apparatus, the combination of an elevated structure, a plaster board forming mechanism mounted to travel longitudinally thereof, receivers disposed beneath said structure, and a conveyer secured to said plaster board forming mechanism so that the delivery end may be raised and lowered. 115

17. In plaster board apparatus, the combination of an elevated structure, a plaster board forming mechanism mounted to travel 125 longitudinally and transversely thereof, receivers disposed beneath said structure, a conveyer secured to said plaster board forming mechanism so that its delivery end may be raised and lowered. 130

18. In plaster board apparatus, the combination of an elevated way, a platform mounted thereon to travel longitudinally thereof, plaster board forming mechanism, 5 mounted to travel on said platform transversely of said way, receivers disposed beneath said structure, and a conveyer secured

to said plaster board forming mechanism so that its delivery end may be raised and lowered.

10

In witness that I claim the foregoing I have hereunto subscribed my name this 30th day of April, 1920.

JOHN SCHUMACHER.
